(57) **CLAIM**

The ornamental design for an electrical connector holder, as shown and described.

DESCRIPTION

FIG. 1 is a front, top and left side perspective view of an electrical connector holder showing our new design; FIG. 2 is a front, bottom and left side perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a left side view thereof.

The broken lines illustrate portions of the electrical connector holder that form no part of the claimed design. The dash-dotted lines denote the boundary of the claim and form no part of the claimed design.

1 Claim, 7 Drawing Sheets
